UNITED STATES PATENT OFFICE.

CURTIS C. GRIMES, OF KANSAS CITY, MISSOURI.

PRESSURE-EQUALIZER.

No. 801,236.

Specification of Letters Patent.

Patented Oct. 10, 1905.

Application filed November 27, 1903. Serial No. 182,705.

To all whom it may concern:

Be it known that I, CURTIS C. GRIMES, a citizen of the United States, residing at Kansas City, in the county of Jackson and State of Missouri, have invented certain new and useful Improvements in Pressure-Equalizers, of which the following is a specification.

My invention relates to improvements in pressure-equalizers; and it consists in a main body and two or more resilient members connected together and to the main body in such a way that when any portion of the pressure-receiving surface of the main body is acted upon the entire body will yield in a uniform manner instead of simply that particular portion to which the pressure is applied.

One advantage of the above construction is that the entire pressure-receiving surface of the main body is retained in the same plane when in its normal position and when subjected to pressure. For instance, if pressure be applied to one corner of the main body said corner will not alone yield, but the entire body will yield to the same degree under the pressure.

A further advantage is that all the resilient members employed synchronously resist the pressure applied and can therefore be made of lighter material than if they were acted upon separately.

Other advantages of the invention will hereinafter appear, and in order that it may be fully understood reference will now be made to the accompanying drawings, in which—

Figure 1 shows a perspective view of a bedstead provided with my improvements. Fig. 2 is an inverted plan view of the same. Fig. 3 is a transverse section taken on line III III of Fig. 2. Fig. 4 shows the device arranged in the form of a spring-mattress. Fig. 5 is a detail of a connecting-bar which is secured to the supporting members to cause their simultaneous operation.

In said drawings, 1 designates the main body, which in this instance is shown in the form of an ordinary bed-frame, comprising side and end rails 2 and 3, head and foot boards 4 and 5, and slats 6.

7 designates a pair of transverse supports located near the opposite ends of the main body and comprising a top portion 8 and oppositely-disposed depending flanges 9, which are preferably extended the full length of said supports.

10 designates tubular supporting-legs arranged in pairs and pivotally mounted at their adjacent flanged portions 11 upon pins 12 and 12^a, extending transversely through the depending flanges 9. The outer ends of the supporting-legs are curved downwardly, as shown in Figs. 1 and 3, and provided with ball-bearing casters 13, which permit the supporting-legs to readily expand and contract when the main body is subjected to and relieved of pressure.

The inner ends of flanged portions 11 overlap and are pivotally secured to rods 14, formed upon the opposite ends of a connecting-bar 15, which latter also carries pins 12^a. Rods 14 operate in slots 16 in the depending flanges and are embraced by coil-springs 17, the ends 18 of which extend in opposite directions and pressing downwardly on pins 12 and 12^a normally hold rods 14 and the inner ends of the supporting-legs in an elevated position, as shown in Fig. 1.

By applying downward pressure upon one end of main body 1 the supporting-legs beneath said end will be expanded by said pressure, and in turning on pins 12 and 12^a their inner overlapping ends are depressed and carry therewith rod 14, that partly rotates the connecting-bar 15, which in turn depresses rod 14 at its opposite end, which thereby expands the supporting-legs, to which it is pivotally connected. The supporting-legs are held in alinement while being thus simultaneously depressed by the oppositely-disposed depending flanges 9 and are thereby prevented from exerting lateral pressure on and bending pins 12 and 12^a. The depression of rods 14 increases the tension on springs 17, so that when the main body is relieved of its load said springs will immediately relax and contract the supporting-legs which elevate the main body to its normal position.

In Fig. 4 the main body 1^a is relieved of the head and foot boards 4 and 5, and the supporting-legs are made straight and provided at their lower ends with antifriction-rollers 13^a, which rest upon transverse slats 6^a of the bed-frame, so the supporting-legs may readily expand and contract, as above described, when the main body is subjected to pressure.

By substituting my device for the usual spring-mattress a very comfortable bed is obtained, because its upper surface is always smooth whether in an elevated or depressed

position. Consequently the ridges and depressions common with ordinary mattresses after more or less use are obviated.

While I have shown the device applied to 5 a bedstead and a spring-mattress, it is obvious that it can be employed to advantage as a buffer or for supporting car-bodies, wagon-bodies, and a variety of other purposes not necessary to mention.

10 From the above description it is apparent that I have produced a device which is simple, cheap, and durable in construction and thoroughly effective for the purpose intended.

Having thus described my invention, what 15 I claim, and desire to secure by Letters Patent, is—

1. In a device of the character described, a main body, resilient members pivotally secured thereto, and a connecting-bar pivotally 20 securing the resilient members together and pivotally securing a number of said members to the main body.

2. In a device of the character described, a main body, resilient members arranged in 25 pairs pivotally secured to said main body and each pair having overlapping ends, and a connecting-bar pivotally securing said overlapping ends together and pivotally securing a number of the resilient members to the main 30 body.

3. In a device of the character described, a main body, transverse supports secured thereto, resilient members pivotally secured to said supports, and a connecting-bar pivotally 35 securing the resilient members together and pivotally securing a number of said members to the transverse supports.

4. A device of the character described, consisting of a main body, resilient supporting- 40 legs pivotally secured at their upper ends to said body, a connecting-bar pivotally securing said supporting-legs together and piv-

otally securing a number of them to the main body, and antifriction-rollers secured to the lower ends of said supporting-legs. 45

5. In a device of the character described, a main body, supporting-legs pivotally secured in pairs to the opposite ends of the main body having overlapping upper ends, a connecting-bar, rods projecting from the opposite ends thereof, pivotally connecting the overlapping upper ends of the legs, pins also projecting from the opposite ends of the connecting-bar pivotally connecting one of each pair of legs to the main body, and means for normally holding the upper ends of the legs in an elevated position. 50

6. In a device of the character described, a main body, supporting-legs pivotally secured in pairs to the opposite ends of the main body 60 having overlapping upper ends, a connecting-bar, rods projecting from the opposite ends thereof pivotally connecting the overlapping upper ends of the supporting-legs, pins also projecting from the opposite ends of the bar 65 pivotally connecting one of each pair of supporting-legs to the main body, springs for normally holding the upper ends of the supporting-legs in an elevated position, and antifriction-rollers secured to the lower ends of 70 the supporting-legs.

7. In a device of the character described, a main body, transverse supports secured thereto provided with depending flanges, pins extending transversely through said flanges, 75 and resilient members operatively connected together and pivotally mounted upon the transverse pins.

In testimony whereof I affix my signature in the presence of two witnesses.

CURTIS C. GRIMES.
